UNITED STATES PATENT OFFICE.

ARNO ANDREAS, OF MUNSTER, GERMANY.

COMPOUND DRUM MILL.

Application filed September 14, 1925, Serial No. 56,168, and in Germany October 11, 1924.

This invention is an improvement in that type of compound drum mills in which there are separate compartments for the preliminary grinding and the finer grinding of 5 the material.

The main object of the invention is to provide a simple and automatically acting mechanism for separating the coarser material delivered from the preliminary grinding compartment, and to return said coarser material to said compartment while separating out the finer material and advancing it to the next successive compartment in which the material is to be more finely ground.

15 In carrying out my invention I provide an arrangement of partitions, certain of them being solid and others being perforated, and an arrangement of screens whereby the rotation of the parts carrying said partitions 20 and screens acts to automatically separate the coarse and fine material and deliver the two grades in opposite directions, one to the preliminary grinder, and the other to the finer grinder.

25 As one important feature of my invention I provide conducting chambers encircled by an annular compartment in which the screening of the material takes place. By means of radially arranged partitions in the 30 conducting chambers, the latter are divided into compartments, and the annular screening compartment is likewise divided into chambers by solid and screening partitions in such a way that the material is delivered 35 from one conducting chamber to the annular screen carrying compartment, and the coarser particles are returned from the latter to the same conducting chamber, while the finer material is delivered through the other 40 conducting chamber.

As a further important feature the annular screening compartment with its screens may be so designed that the screen surface is considerably increased, and a more efficient 45 screening operation is secured. This may be accomplished by making the chamber of greater width than the distance between the grinding chambers and/or by setting the transversely disposed screen at an 50 angle, whereby the screening surface is not only increased, but a double screening action is obtained during the rotation of the parts. The screens may be oblique to the drum axis, or approximately tangential.

55 As a further important feature the screens

are so positioned and mounted that they may be readily removed from the exterior for replacement and repair.

As a further important feature certain of the chambers in the annular screening compartment may be provided with guides, whereby comparatively small orifices may be employed for the entrance and delivery of the material.

Other important features and advantages 65 of my improved construction will be pointed out hereinafter, or will be apparent from a consideration of the specific constructions illustrated in the accompanying drawings.

In these drawings:

Fig. 1 is a central longitudinal section of 70 a construction embodying my invention.

Fig. 2 is a transverse section on the line 2—2 of Fig. 1.

Fig. 3 is a development of a portion of 75 the wall of the conducting chambers, and showing the relationship of the outlet and inlet orifices to the screening compartment.

Fig. 4 is a central longitudinal section 80 showing a modified form.

Fig. 5 is a transverse section on the line 5—5 of Fig. 4.

Fig. 6 is a development of the wall of 85 the conveying chamber showing the obliquely set partitions and screen walls of the screening compartment.

Fig. 7 is a transverse section through a screening compartment with tangential or approximately tangential arrangement of partitions and screens.

Fig. 8 is a detail showing a slightly modified form of screen.

Fig. 9 is a section similar to Fig. 7, but showing guides for directing the material to the outlet orifices, and

Fig. 10 is a detail showing the conducting 95 guides in outline.

My improved construction is adapted to be employed in any type of rotary grinding mill, and between a preliminary grinding 100 chamber *a* and a fine grinding chamber *b*. By the terms "preliminary grinding" and "fine grinding" I do not mean to imply that the mill grinds in merely two stages, as there may be a series of grinding chambers, each producing a finer grade of material, and my improved construction may be employed between each two successive grinding chambers.

In Fig. 1 I have shown two of these sep- 110

arators with the intermediate grinding chamber mainly broken away. The main drum has a pair of walls e and e_1 forming therebetween a pair of conducting chambers c and d . The partition e between the conducting chamber c and the preliminary grinding chamber a is provided with slots or other apertures f for the entrance of the crushed material from the grinding chamber a to the conducting chamber c . It also has a central opening g for the return of the coarse particles which have not passed through the screens hereinafter referred to. The wall e_1 between the conducting chamber d and the fine grinding chamber b has merely a central opening g_1 for the delivery therethrough of the material which has passed through the screens. The conducting chambers c and d are each subdivided into a plurality of chambers i by means of radially extending partitions h . The two chambers c and d may be separated by a transverse partition e_2 , that is, a partition at right angles to the axis of rotation of the device.

Encircling the conducting chambers c and d is an annular compartment k which serves as the screening chamber. This is subdivided into a plurality of compartments s by radially disposed solid partitions l and intermediate screening partitions m . Thus each alternate partition in the annular chamber k is solid, while the remaining ones are perforated to serve as screens. The number of partitions in the annular compartment is preferably double the number of chambers in each conducting compartment, and each screen m comes approximately opposite to a partition h while the solid partitions m come intermediate of two partitions h .

The peripheral wall of the conducting compartments, which serves as the inner wall for the annular screening compartment, is provided with a series of orifices n and o . The orifices n communicate with the conducting compartment c and are in front of the screens m , while the orifices o are behind the screens and communicate with the conducting chamber d , as shown more particularly in the development Figure 3. In the center of the apparatus is a pair of oppositely facing conical deflectors for causing material which drops through the orifices n and o to be deflected or directed to the openings g and g_1 respectively.

The peripheral wall t of the annular screen compartment k may be provided with openings adjacent to the several screens, and normally tightly closed by doors or valves z whereby the screens may be removed for cleaning or repair. In Fig. 2 I have indicated two of these sets of screen compartments with the delivery and receiving chambers, and have indicated the screen in the

second one as being of finer mesh than that of the first one, considered in the direction of travel of the material. Obviously these two may be spaced at any desired distance apart, and there may be a series of them with successively finer screens.

In the operation of the construction hereinbefore described, the material which is crushed in the preliminary grinding chamber a enters the conducting chamber c through the slots f as indicated by arrows at the lower left hand side of Fig. 1, and passes through the chambers i and openings n into the screening chambers s . As the construction rotates, the material is carried toward the upper side of the apparatus while the fine material falls through the screen or sieve into the adjacent chamber s , and thereafter falls through the opening o into a chamber i to the second conducting chamber d , whereby it is deflected through the opening g_1 by the deflector p . The coarser material which has not passed through the screens m returns through the openings n when the latter are at the upper side of the apparatus, and is directed back to the preliminary grinding chamber a through the opening g by the deflector p . Thus the material is automatically separated into two grades, the finer being advanced to the next grinding chamber, while the coarser part is returned for regrinding. The partitions e and e_1 may be provided with pipes extending axially in opposite directions from the openings g and g_1 so as to conduct the material away from the partitions to the center of the grinding chambers. This is more important for the partition e as it prevents the immediate return of such material through the openings f .

To facilitate the introduction and removal of the screens m the peripheral wall may be provided with slots r normally closed by sliding valve plates z_1 , as shown in Figs. 4, 5 and 6. At the lower portion of Fig. 4 I have shown one of these valve plates pulled out axially, and the screen moved outward radially from its normal position.

In order to increase the area of the screening surface the screens m and the solid partitions l may be arranged obliquely, as indicated in Fig. 6. The operation is substantially the same as hereinbefore described, except that due to the oblique setting of the screens the material is caused to travel along the screen through a greater distance, and more efficient screening operation is effected. The effective screening action may be also increased by making the screening chamber of greater axial length than the distance between the partitions e and e_1 , as shown in Fig. 4.

In Fig. 7 I have illustrated a further arrangement of screening and solid partitions in the annular screen compartment. Here

the screens *m* and partitions *l* extend tangentially or approximately tangentially. Thus as the material passes through an opening *n* at the lower side of the apparatus, it will be caused to travel over the screen as indicated by the arrow *I*, and as the device rotates clockwise the screen reaches such a position that the material travels in the opposite direction along the screen to the same opening, as indicated by the arrow *II*. The finer material passing through to the screen, falls on the partition *n* and is directed to the opening *o*. This movement of the material back and forth across the screen insures a substantially complete removal of the finer material. These screens and partitions need not be straight, as indicated in the forms hereinbefore specifically referred to, but may be curved and of an approximate tangential positioning as indicated in Fig. 8.

In order to direct the material to the openings *o* and insure the substantially complete return of the coarser particles, the solid partitions *l* may be provided with guides or baffles as indicated in Figs. 9 and 10. Metal plates *w* may be inclined in opposite directions to each opening *n*, as shown in Fig. 10, and may be curved in an arc connecting the radial partition *l* and the peripheral wall *t*, as shown in Fig. 9. These curved guides *w* may constitute the solid partitions and permit of the elimination of the straight radial partitions *l*.

Having thus described my invention, what I claim as new and desire to secure by Letters Patent is:

1. A compound drum mill having a peripheral wall encircling a preliminary grinding chamber, and a fine grinding chamber, an annular screening chamber encircling said wall and having transversely disposed screens, means for conducting to said screening chamber material from the preliminary grinding chamber, means for delivering from said screening chamber the material passing through said screens, and means for returning to the preliminary grinding chamber the material which does not pass through said screens.

2. A rotary drum mill having a preliminary grinding chamber, a fine grinding chamber in axial alignment therewith, an annular screening chamber intermediate of said grinding chambers and encircling the drum, a conveying chamber for delivering material from said preliminary grinding chamber to said screening chamber, and for returning to said preliminary grinding chamber the coarse material from the screening chamber, and a conveying chamber for delivering fine material from said screening chamber to said fine grinding chamber.

3. A compound drum mill including a preliminary grinding chamber and a fine

grinding chamber in axial alignment, an annular screening chamber having a plurality of transversely disposed screens, and a pair of axially spaced conducting chambers separated by a partition extending transversely of the axis of the mill, one serving for the delivery of material from the preliminary grinding chamber to the screening chamber, and also for the return of coarse material from the screening chamber to the preliminary grinding chamber, and the other serving for the delivery of fine material from the screening chamber to the fine grinding chamber.

4. A rotary drum having axially spaced preliminary grinding and fine grinding chambers, an annular screening chamber encircling the drum between said grinding chambers and having transverse partitions extending in a direction having a radial component, and conducting chambers from each of said grinding chambers to said screening chamber.

5. A rotary drum having axially spaced preliminary grinding and fine grinding chambers, an annular screening chamber encircling the drum between said grinding chambers, and having transversely disposed, alternately arranged screens and solid partitions, a pair of conveying chambers axially spaced and separated by a transverse partition, one connecting said preliminary grinding chamber and said screening chamber adjacent to one side of each of said screens, and the other connecting said fine grinding chamber and said screening chamber adjacent to one side of each of said solid partitions.

6. A rotary drum having axially spaced preliminary grinding and fine grinding chambers, an annular screening chamber encircling said drum between said grinding chambers, and having alternately arranged, transversely disposed screens and solid partitions, forming an annular row of compartments, a pair of conveying chambers axially spaced by a transverse partition, one connecting each alternate compartment with said preliminary grinding chamber, and the other connecting the remaining compartments with the fine grinding chamber.

7. A rotary drum having axially spaced preliminary grinding and fine grinding chambers, three spaced, transverse partitions forming a pair of intermediate conveying chambers between said grinding chambers, an annular screening chamber encircling said conveying chambers and having a cylindrical inner wall and transversely disposed, alternately arranged solid partitions and screens, said drum having a pair of annular rows of apertures in said wall, one connecting one of said conducting chambers with said screening chamber at points adjacent to each screen, and the other row connecting

- 4
- the other conducting chamber and said screening chamber adjacent to each of said solid partitions.
8. A rotary drum having a pair of axially spaced, transverse partitions, one having a central aperture and the other having a central aperture and additional apertures, said drum having a preliminary grinding chamber adjacent to said last mentioned partition,
- 5 10 and a fine grinding chamber on the opposite side of the other partition, the space between said partitions serving as conducting chambers, and having radially disposed, axially extending partitions, a screening
- 15 chamber encircling the drum and having alternately arranged, transversely disposed perforate and imperforate walls, the wall of said drum having a series of apertures adjacent to the first mentioned partition and to
- 20 the said imperforate walls, and a second pair of apertures adjacent to the second mentioned partition and the perforate walls.
9. A construction as defined in claim 8, in which there are provided a pair of oppositely facing, conical deflectors between said partitions, for directing material through the central openings of said partitions.
10. A construction as defined in claim 3, in which the screening chamber is provided
- 30 with openings and the screens are detachably mounted for removal through said openings.
11. A construction as defined in claim 3, in which the peripheral wall of the screening chamber is provided with slots adjacent
- 35 to each screen, and movable members normally closing said slots.
12. A compound drum mill having an imperforate transverse partition, a partition upon one side thereof and having a central aperture, a partition upon the opposite side thereof and having a central aperture
- 40 and additional apertures, said partitions forming two axially spaced conducting chambers, a screening chamber encircling the drum and having two rows of apertures, 45 one communicating with one conducting chamber and the other communicating with the other conducting chamber, said apertures being arranged alternately in a circumferential direction, and said screening chamber 50 having alternately arranged screens and partitions disposed between successive apertures.
13. A compound drum mill including a preliminary grinding chamber, a fine grinding chamber, an annular screening chamber having two sets of apertures in its inner wall, a conducting chamber leading from one set of apertures to the preliminary grinding chamber, a conducting chamber leading from 60 the other set of apertures to the fine grinding chamber, transversely disposed screens in said screening chamber, transversely disposed partitions in said screening chamber between successive screens, and guides in said screening chamber for delivering coarse material to said first mentioned set of apertures.
14. A compound drum mill including a preliminary grinding chamber, a fine grinding chamber, three axially spaced intermediate partitions forming a pair of conducting chambers between said partitions, one
- 70 communicating with the preliminary grinding chamber, and the other with the fine grinding chamber, and an annular screening chamber encircling said conveying chambers, and of greater axial length than the distance between said partitions.
- Signed this 26th day of August A. D. 1925.

ARNO ANDREAS.
